DRIER

Clifford E. Ives, Chicago, Ill., assignor to Sears, Roebuck and Co., Chicago, Ill., a corporation of New York

Application January 2, 1937, Serial No. 118,879

4 Claims. (Cl. 34—12)

My invention relates to driers and is especially adapted for the drying and curing of textile articles which have been impregnated with a plastic material such as latex or the like. Thus, for example, driers embodying my invention are especially suitable for the drying and curing of goods of the type described in my copending application Serial No. 87,868, filed June 29, 1936, and coated on a machine of the type set forth in my copending application, Serial No. 172,937, filed November 5, 1937.

An object of my invention is to provide a continuous oven which will receive articles to be dried and which will automatically convey said articles through the oven at a predetermined rate of speed so that when said articles are discharged from the oven they will be substantially dry and cured.

A further object is to provide such an oven with means for controlling air circulation through the various portions thereof.

Another object is to provide a device of the type referred to which will be simple in construction, efficient in operation, inexpensive to manufacture and to operate, of easy access for cleaning and repair, and generally satisfactory for the purposes desired.

Various other objects and advantages will become apparent as the description proceeds.

Referring now to the drawings forming part of this specification and illustrating a preferred embodiment of my invention:

Fig. 1 is a top plan view of a drier embodying my invention, parts being broken away to show the interior construction thereof;

Fig. 2 is a side elevational view of the same;

Fig. 3 is an end elevational view thereof taken from the left-hand end of Figs. 1 and 2;

Fig. 4 is a sectional view taken substantially along the line 4—4 of Fig. 2;

Fig. 5 is a sectional view taken substantially along the line 5—5 of Fig. 2;

Fig. 6 is a sectional view taken substantially along the line 6—6 of Fig. 5;

Fig. 7 is a sectional view taken substantially along the line 7—7 of Fig. 5;

Fig. 8 is a sectional view taken substantially along the line 8—8 of Fig. 2;

Fig. 9 is a sectional view taken substantially along the line 9—9 of Fig. 8;

Fig. 10 is a sectional view taken substantially along the line 10—10 of Fig. 9;

Fig. 11 is a sectional view taken substantially along the line 11—11 of Fig. 4; and

Fig. 12 is an enlarged sectional view, partly in

elevation, taken substantially along the line 12—12 of Fig. 11.

Fig. 13 is a sectional view along line 13—13 of Fig. 10, and

Fig. 14 is a sectional view along line 14—14 of Fig. 10.

In the preferred embodiment illustrated, the drier embodying my invention comprises a casing indicated generally by the numeral 10, said casing being preferably in the form of an elongated rectangular parallelopiped having double walls throughout. Thus, the cabinet 10 comprises side walls 13, 13, a bottom wall 14, a top wall 15, and end walls 16 and 17. All of these walls may be substantially similar in construction, preferably comprising spaced sheet metal members 19, 19, the space between these members being filled with insulating material 20 such as rock wool or the like and the walls being reinforced as by beams 21. To reduce cost of construction, the outer members 19 may be made of plywood or other inexpensive sheet material.

Extending longitudinally of the oven on opposite sides thereof are air chambers 23, 23', said chambers extending substantially from top 25 to bottom of the casing 10. Said air chambers 23 are separated from that portion of the oven which carries the goods to be dried by means of walls 25 and disposed in said walls 25 at regular intervals are hinged dampers 26 and 26' manually controlled, as by rods 27, said rods extending through apertures in the upper wall of the casing, as at 29.

The space between the longitudinal air chambers 23, which space may be referred to generally 35 as a drying compartment 31, is provided with a plurality of baffles 32, 32', said baffles being secured respectively by means of brackets 33 to beams 35 extending at intervals across the top of the compartment 31. The baffles 32 and 32' 40 may be formed conveniently of sheet metal, such as galvanized iron or the like, and, as seen clearly in Fig. 4, extend alternately from the top and bottom of the compartment, the baffles 32 leaving an opening thereabove while the baffles 32' provide passages therebelow, thus requiring the air which enters the drying compartment 31 through the dampers 26 to travel in a tortuous path above and below the baffles.

The drying compartment 31 is preferably closed at the top by means of hatch covers 37, said covers being preferably double walled and insulated like the walls of the oven and provided with handles 38, whereby the hatch covers may be

completely removed to permit access to the interior of the oven.

The material to be dried is preferably carried by a conveyor belt 40. This belt may be formed of any suitable material, but I have found that the best material for my purpose is a tape formed of a high quality of spring steel. This material, by reason of its temper, will stand the relatively high temperatures of the oven without losing its 10 resilience and without becoming appreciably brittle. Hence, loss of time due to shutdowns is substantially minimized by the use of such material.

The conveyor belt or tape 40 is actuated by means of a motor 41 which operates through pulleys or sprocket wheels 42, said pulleys or sprocket wheels being carried on shafts 43 which are suitably journaled in the floor of the drying compartment 31 and carry drums 45 formed of sheet metal or other suitable material.

20 The conveyor belt or tape 40 enters the drying compartment, as shown best in Fig. 9 through an opening 46 closed by a pair of resilient inwardly extending wings 47 formed of sheet metal or the like, whereby loss of hot air from the oven 25 is substantially prevented. The conveyor leaves the drying compartment through an exit opening 48 closed by similar outwardly extending wings 49. The conveyor is trained over pulleys 50 at the open end of the oven.

30 Throughout the length of the drying chamber 31 the conveyor 40 is carried by means of channel shaped guides 52 (Figs. 11-12) secured as by welding or soldering to the top or cross flange of T-members 53, a T-member 53 extending the entire length of the drying chamber 31 for each run of the conveyor 40. Said T-members are supported by uprights 54 which may be strap iron or the like, the latter being secured to the floor of the drying chamber as at 55, the 40 T-members being secured to said uprights as by rivets 56 or the like. The junctions between the T-members and uprights are braced by means of a triangular sheet metal gusset 57. These members 57, which may be formed of galvanized iron or the like, preferably extend forwardly of each of the uprights 54 as seen best in Fig. 11, and serve to divide the fabric sections as they approach to prevent possible jamming thereof against the upright.

50 Secured on opposite sides of the T-members (Fig. 12) as by rivets 56, are longitudinal sheet strips 58, 58, for the purpose of guiding the fabric sections past the uprights 54. These strips 58 have a tapered lower edge 59 at the leading end 55 of each run of the conveyor. (See Fig. 10.) I also provide at the leading end of each run an approximately cylindrical notched divider 60 secured to the top flange of the T-bars 53. (Figs. 13 and 14.)

60 The conveyor tape is trained around the cylinders 45 at the closed end of the oven and around similar vertically journaled cylinders 61 at the open end, i. e., the receiving and discharging end, where said tape changes direction.

65 Any suitable means may be provided for circulating hot air through the oven for drying and curing the material which is conveyed therethrough. In the embodiment shown, a U-shaped duct 62 conducts a current of air from the top 70 of the oven, at a point intermediate the length thereof, approximately adjacent the middle, to a heating chamber 63 which is warmed by any suitable means, preferably by an oil burner. The burner is operated by means of a motor 64. 75 From the heating chamber 63 the air passes

through a duct 67 in which is interposed a blower 68 operated by a motor 69. The air which has been heated reenters the oven through the flared member 70 to be recirculated within the oven, again passing out of the oven into the U-shaped 5 duct 62. Excess gas may be exhausted through the duct 73.

The operation of the device will be readily apparent. The material which is to be dried and/or cured, for example, latex coated or impregnated 10 garment sections, enters the oven on the conveyor 40 through the opening 46 and is conveyed through the oven by the conveyor tape, making several runs or courses through the length of the oven, the total course of travel through the oven 15 and the speed of the conveyor being so coordinated that the goods will be thoroughly dried and cured by the time it is discharged by the conveyor through the opening 48.

As the material travels through the oven it will 20 be impinged upon by transversely traveling currents of hot air. The air which is admitted to the oven through the flared member 70 travels along the channels 23, escaping into the compartment 31 through the dampers 26, and thereafter traveling across the oven in a tortuous path, 25 passing above the baffles 32 and under the baffles 32', finally escaping through dampers 26' into the channel 23' on the opposite side of the 30 oven into the U-shaped conduit 62.

In the curing of rubber, it is highly advantageous to heat in the presence of steam. According to my invention, the recirculation of heating gas permits the retaining of moisture 35 which has been given off from the goods, in the form of steam, since the interior of the oven is normally kept at a temperature above 212° F., at atmospheric pressure. The use of a recirculating oven is also advantageous inasmuch as 40 heat is thereby conserved.

Various changes coming within the spirit of my invention may suggest themselves to those skilled in the art, and hence I do not wish to be limited to the specific forms shown or uses 45 mentioned except to the extent indicated in the appended claims, which are to be interpreted as broadly as the state of the art permits.

I claim:

1. In combination with means providing an 50 elongated chamber and means for circulating a current of heated air through said chamber, a conveyor comprising a flexible tape mounted for travel longitudinally within said chamber, means for reversing the direction of travel of said tape; 55 said reversing means comprising a vertical journaled cylinder around which said tape is trained, and means independent of said cylinder for supporting said tape.

2. A multi-directional apparatus for treating 60 fabric and other flexible sheet material, comprising a metal tape, smooth-surfaced cylindrical means rotatably mounted and about which said tape is trained flatwise, and means cooperating with said cylindrical means in maintaining said tape longitudinally at a substantial angle to the vertical to prevent the material folded on and depending on opposite sides from the top of said tape from slipping therealong, the second means being operative to maintain said tape substantially vertical flatwise, said tape being yieldable 65 adjacent said cylindrical means so that a suspended side of said material will pass flatwise between a face of said tape and said cylindrical means, a baffled material-treating chamber affording a tortuous path, said cylindrical means 70

75

and tape being mounted and arranged so that said tape travels transversely through said path, and means for supplying said chamber with a material-treating medium to which said material is subjected during its travel therein.

5. 3. A multi-directional conveyor for fabric and other flexible sheet material, comprising a metal tape, smooth-surfaced cylindrical means rotatably mounted and about which said tape is trained flatwise, means cooperating with said cylindrical means in maintaining said tape longitudinally at a substantial angle to the vertical to prevent the material folded on and depending on opposite sides from the top of said tape from slipping, therealong, the second means being operative to maintain said tape substantially vertical flatwise, said tape being yieldable adjacent said cylindrical means so that a suspended side of said material will pass flatwise between a face of said 10 tape and said cylindrical means.

4. A material-treating apparatus comprising a chamber having a floor and a ceiling and two sets of parallel vertical walls, those of one set alternating with those of the other set, those of one set extending upward short of the ceiling 5 and those of the other set extending downward short of the floor and in overlapping relation to those of the first set, an end of each wall of one set terminating short of the chamber wall toward which said ends extend, and an end of each wall of the other set terminating short of the opposite chamber wall toward which the last mentioned ends extend, whereby two intersecting tortuous paths are afforded in substantially the same 10 space of said chamber, means for forcing a material-treating medium along one of said paths and means for moving a material to be treated along the other path.

CLIFFORD E. IVES. 20
